Primary Examiner—B. J. Bullock

[57] CLAIM

The ornamental design for a flower pot cover, as shown and described.

DESCRIPTION

FIG. 1 is a perspective view of a flower pot cover showing my new design;
 FIG. 2 is a side elevational view thereof, all sides being identical;
 FIG. 3 is a top plan view thereof;
 FIG. 4 is a bottom plan view thereof;
 FIG. 5 is a side elevational view of a second embodiment of the design of FIG. 1, the only difference being the height of the body; and,
 FIG. 6 is a side elevational view of a third embodiment of the design of FIG. 1, the only difference being the height of the body.

The flower pot cover has no substantial thickness.
